METHOD OF FORMING ELECTRICAL
CONTACTS

Steven Kobzy, Chicago, Ill.

Application January 18, 1937, Serial No. 121,106

5 Claims. (CL 29—155.55)

The primary object of this invention is to provide an improved method for producing electrical contacts from strips of sheet metal through a series of operations which will involve less time and less waste of material. This is accomplished by utilizing a series of spaced stationary dies and registering, punching, forming and embossing dies carried by the stationary and movable jaws, respectively, of a punch press, and so arranged that a strip of sheet metal advanced a predetermined distance at each actuation of the punch press will form the contact by a series of operations of the dies. This strip may be fed by hand or mechanically.

15 A mechanism suitable for carrying out this invention is fully described in the following specification in conjunction with the accompanying drawings wherein:

Figure 1 is a perspective of one end of a metal strip indicating the several operations to which the strip is subjected as it advances endwise, a completed contact being shown as severed from the forward end of the strip;

Fig. 2 is a plan view partly in section on line 2—2 of Fig. 3 showing the various punching, forming, notching, shearing, and embossing dies used in forming this electrical contact from a strip of sheet metal;

Fig. 3 is a partial vertical section on broken line 3—3 of Fig. 2;

Fig. 4 is a partial vertical section on line 4—4 of Fig. 2 showing a slitting die;

Fig. 5 is a partial vertical section on line 5—5 of Fig. 2 showing a forming die in operation;

Fig. 6 is a partial section on line 6—6 of Fig. 2 showing two forming dies in operation simultaneously;

Figs. 7 and 8 are two partial sections on lines 7—7 and 8—8, respectively, of Fig. 2, showing forming dies in operation, Fig. 8 also having an embossing die operating simultaneously therewith; and

Fig. 9 is an enlarged perspective of the finished electrical contact.

45 The electrical contact for which my improved method of production has been devised is such as may advantageously be employed to receive engagement from one of the prongs of a vacuum tube. As shown best in Fig. 9, this contact C is made of sheet metal having requisite spring properties, formed to provide a mounting plate *a* from which extends a flaring terminal lug *b* of slightly increased width, the lug having one or more holes *b'*, *b*² and an embossed button *b*³; also extending 50 at right angles from the mounting plate, opposite

the terminal lug, is a clip *c* whose angled body is sufficiently wide to provide for turned sides *c'* and *c*² which face each other whereby to grip between them and the clip body, the prong (not shown) of a vacuum tube or other electrical instrument. Ears *d* may be extended outwardly from the clip sides at a point adjacent the mounting plate, as shown.

5 The mechanism illustrated for punching and forming this contact from a strip of metal comprises a series of dies, the stationary element of each die being carried by the stationary jaw 10 of a conventional punch press while the movable members are carried by its movable jaw 11. Inasmuch as a punch press is well known, further 10 description thereof is unnecessary. It is understood, however, that at each actuation of the punch press the movable jaw 11 descends a predetermined distance toward the stationary jaw 10 and then returns to its initial position where- 15 in all of the movable parts of the die are above the strip.

20 Two punches 12, 13 which are preferably round pass through suitable guides 14 and coact with registering openings 15, 16 in a die block 17 which is carried by the stationary jaw 10 to form the holes *b'*, *b*². The guide 14 is separated from the die block 17 leaving a passage 18 through which the metal strip S may be fed endwise either manually, or by means of mechanism not shown, a 25 definite amount at each step. The sides of passage 18 serve also to guide the strip laterally, or, if desired, other guide means may be used.

25 A punch 19 which is secured to the movable jaw 11 coacts with a corresponding opening in 30 the die block. This latter punch is preferably rectangular in form with a recessed portion which leaves an ear 20.

35 At the next operation, when the strip has been advanced toward the left side of the sheet one 35 step, the ear 20 is slotted centrally along the line 21 by means of a punch 22, as shown in Fig. 4, to form the ears *d*. At the same time a notching punch 23 the center of which is preferably in line with the line 21 removes a portion of the left side of the strip so as to outline a portion of the lugs *b* of the finished contacts but leaving a narrow bar 24 to connect adjacent contact blanks. For the sake of convenience, the upper edge of the strip S (Fig. 2) is referred 40 to as the right side and the lower as the left side.

45 At the next stage, and when the strip has been advanced one space, the first forming punch 25 serves to bend down the slotted ears 20 to the 50 55

position 28^a. The lower end of this punch is rounded to serve as a pilot punch for the entire group.

The second forming punch 26 coacts with a stationary forming die 27, as shown in Fig. 3 to cause the parallel slotted portions 28 to be bent vertically into the position 28^a. A plunger 29 is slidably mounted in the block 27 and is pressed by means of a spring 30, the spring resting upon a screw 31. This spring is sufficiently strong to force the edge portions 28^a out of the die block 27 as the punch 26 recedes. It will be observed also that the upper surface of the die block 27 is slightly raised, so that as the strip is advanced it slides up over the surface 27^a. Another forming punch 32 serves to curve the lug b as shown in Fig. 6 on the curved die surface 27^b.

As the strip is again advanced one step, the edge portions 28^a of the right hand end are engaged by a third forming punch 33 whose lower surface is provided with a V-notch 34. As the forming punch 33 descends it presses the right hand end of the contact down against a stationary block 35 and, as it continues to descend, forces the edges 28^a inwardly from the dotted line position to the full line position 28^b, as shown beneath the punch 33 completing the clip c.

The block 35 is provided with a spring pressed plunger 36 similar to the plunger 29. During this forming operation the plunger 36 is pressed down, as shown, against the action of a spring 37, but as soon as the die rises, the spring 37 will push the plunger 36 up, lifting the right hand end of the formed contact out of the block 35.

As the strip is advanced one more step it reaches the position shown by the section line 7—7 of Fig. 2 wherein the right hand end falls beneath a fourth forming punch 38 which passes between the inwardly bent edges 28^b and bends the clip c down over a ledge 39 until it assumes a position 28^c substantially at right angles to the mounting a of the contact, as shown in Fig. 1.

At the next and last stage, as shown by the section line 8—8, the body of the contact is given another bend of substantially 90° about a stationary ledge 40 by means of a fifth forming punch 41 carried by the movable jaw 11. At the same time the body of the contact is embossed to form the button b³ by means of an embossing punch 42, as shown in Fig. 3, cooperating with a depression 43 in a stationary die 44 which carries the ledge 40.

At the same time the finished contact C is completed by means of a shear 45 which cuts away the bar 24 connecting the last contact with the next adjacent contact as indicated by the dotted lines 24.

According to the method of procedure herein described, the contacts in question may be produced economically as regards the material used and the time consumed.

I claim:

1. The method of forming contacts of the class described from a sheet metal strip comprising arranging a series of punching and forming dies in spaced alignment, the steps in order comprising punching the left side of the strip in what is later one end of the contact, punching out an intermediate portion midway between two contacts leaving therebetween an inwardly extending ear, slitting from the right edge of the strip through said ear, notching the left side of the strip, passing a forming die through the punched opening in the intermediate portion to bend down the slotted ear, bending up two slotted portions from the right side of the strip including said ears, bending said portions toward each other, bending the right hand end of the contact about a first line parallel to the edge of the strip, bending the right hand end of the strip about a second line parallel to the first line and at the left thereof so as to space the two end portions of the contact from each other, and severing the last contact from the strip.

2. The method of forming contacts of the class described from a sheet metal strip comprising arranging a series of punching and forming dies in spaced alignment, the steps in order comprising punching the left side of the strip in what is later one end of the contact, punching out an intermediate portion midway between two contacts leaving therebetween an inwardly extending ear, slitting from the right edge of the strip through said ear, simultaneously notching the left side of the strip, passing a forming die through the punched opening in the intermediate portion to bend down the slotted ear, bending up two slotted portions from the right side of the strip including said ears, bending said portions toward each other, bending the right hand end of the contact about a first line parallel to the edge of the strip, bending the right hand end of the strip about a second line parallel to the first line and at the left thereof so as to space the two end portions of the contact from each other, and severing the last contact from the strip.

3. The method of forming contacts of the class described from a sheet metal strip comprising arranging a series of punching and forming dies in spaced alignment, the steps in order comprising punching the left side of the strip in what is later one end of the contact, punching out an intermediate portion midway between two contacts leaving therebetween an inwardly extending ear, slitting from the right edge of the strip through said ear, simultaneously notching the left side of the strip, passing a forming die through the punched opening in the intermediate portion to bend down the slotted ear, bending up two slotted portions from the right side of the strip including said ears, bending said portions toward each other, bending the right hand end of the contact about a first line parallel to the edge of the strip, bending the right hand end of the strip about a second line parallel to the first line and at the left thereof so as to space the two end portions of the contact from each other, and severing the last contact from the strip.

4. The method of forming contacts of the class described from a sheet metal strip comprising arranging a series of punching and forming dies in spaced alignment, the steps in order comprising punching the left side of the strip in what is later one end of the contact, punching out an intermediate portion midway between two contacts leaving therebetween an inwardly extending ear, slitting from the right edge of the strip through said ear, notching the left side of the strip passing a forming die through the punched opening in the intermediate portion to bend down the slotted ear, bending up two slotted portions from the right side of the strip including said ears, simultaneously bending up the left hand end of the contact, bending said portions toward each other, bending the right hand end of the strip about a second line parallel to the first line and at the left thereof so as to space the two end portions of the contact from each other, and severing the last contact from the strip.

5. The method of forming contacts of the class described from a sheet metal strip comprising arranging a series of punching and forming dies in spaced alignment, the steps in order comprising punching the left side of the strip in what is later one end of the contact, punching out an intermediate portion midway between two contacts leaving therebetween an inwardly extending ear, slitting from the right edge of the strip through said ear, notching the left side of the strip passing a forming die through the punched opening in the intermediate portion to bend down the slotted ear, bending up two slotted portions from the right side of the strip including said ears, simultaneously bending up the left hand end of the contact about a first line parallel to the edge of the strip, bending said portions toward each other, bending the right hand end of the strip about a second line parallel to the first line and at the left thereof so as to space the two end portions

of the contact from each other, embossing, and severing the last contact from the strip.

5. The method of forming contacts of the class described from a sheet metal strip comprising arranging a series of punching and forming dies in spaced alignment, the steps in order comprising punching the left side of the strip in what is later one end of the contact, punching out an intermediate portion midway between two contacts leaving therebetween an inwardly extending ear, slitting from the right edge of the strip through said ear, notching the left side of the strip so as to leave only a narrow bar connecting the adjacent contacts, passing a forming die through the punched opening in the intermediate portion to bend down the slotted ear, bending up two slotted portions from the right side of the strip, bending said portions toward each other, bending the right hand end of the 5 contact about a first line parallel to the edge of the strip, bending the right hand end of the strip about a second line parallel to the first line and at the left thereof so as to space the two end portions of the contact from each other, and cutting out the connecting bar thereby severing the last contact from the strip. 10
